UNITED STATES PATENT OFFICE.

ELMER O. ROBERTS AND RAYMOND F. DOTSCH, OF OLYMPIA, WASHINGTON.

HINGE.

Application filed June 27, 1922. Serial No. 571,148.

To all whom it may concern:

Be it known that we, ELMER O. ROBERTS and RAYMOND F. DOTSCH, citizens of the United States of America, residing at 5 Olympia, in the county of Thurston and State of Washington, have invented certain new and useful Improvements in Hinges; and we do hereby declare that the following is a full, clear, concise, and exact description of the invention, such as will enable others skilled in the art to which it appertains to make and use the same.

This invention relates to improvements in hinges, having for an object to provide a hinge especially designed for use in the hinging or pivoting of the legs of a folding or collapsible table to the top section of the same, being of such construction as will permit of the swinging of the leg engaged 15 thereby to position adjacent and in substantial parallelism to the top section when not in use and to permit swinging of the leg in a reverse direction into a position at substantially right angles to said top section, where- 20 at the squared upper end of the leg will engage or abut an adjacent portion of said top section for rigidly supporting it.

It is likewise an object of the invention to provide a table leg hinge which is of such 25 construction and design as will firmly retain the leg in a "set up" position with relation to the table top section, means being provided for locking the hinge in that position and by consequence, prevent undesired col- 30 lapsing of the table.

Other objects will be in part obvious and in part pointed out hereinafter.

In order that the invention and its mode 35 of operation may be readily understood by persons skilled in the art, we have in the accompanying illustrative drawings and in the detailed following description based thereon, set out one possible embodiment of the same.

In these drawings:

Figure 1 is a side elevation of a folding table equipped with the improved hinge;

Figure 2 is an enlarged fragmentary detail in elevation showing the position of the hinge when the leg is in folded position together with the position of the hinge when the leg is in "set up" position, the latter being shown in dotted dash lines; and,

Figure 3 is a fragmentary detail in perspective of the improved hinge, showing its

position when the table leg is in a "set up" position.

Having more particular reference to the drawings, in connection with which like characters of reference will designate corresponding parts throughout, 1 represents the top of a foldable table provided with the usual number of legs 2 for supporting the same. In order that said legs 2 may be hingedly connected to the under side of the table 60 top 1, the invention is utilized, and in this direction, may be stated to comprise a substantially right angularly formed strap metal arm 3 having bearing sleeves 4 formed upon the top of its ends while openings 5 are 65 formed in the right angularly disposed portions of the same and serve for a purpose which will be subsequently described.

Attaching fingers or plates 6 and 7 are provided the device and have each a bearing sleeve 8 upon certain of their extremities adapted to be received between the spaced bearing sleeves 4 on the opposite ends of the arm 3, whereby a pintle or pivot pin 9 may be passed therethrough for 70 an obvious purpose. Also, outwardly disposed staples or eyelets 10 are fixedly carried upon the outer surfaces of these attaching fingers or plates 6 and 7 and are 75 so positioned as to be received through the opening 5 in the angularly disposed portion of the arm 3 when the hinge is in such position as to retain the table leg 2 in its "set up" or supporting position.

In this connection, it is to be noted that 80 the attaching finger of plate 6 is secured to one side of the upper end of the table leg 2, while the attaching finger of plate 7 is secured to a portion of the under side 85 of the table top 1 in proximity to one end portion of the same as clearly shown in the Figure 3. Thus, when the leg 2 is in its folded or non-supporting position, the same will be arranged adjacent the normally upper side of the table top 1 and in 90

substantial parallelism thereto as shown in the Figure 2, inasmuch as the longer angular portion of the arm 3 will correspond to that distance between its outer end and the adjacent end of said table top and will permit said leg to be swung outwardly and then upwardly to a position adjacent said normally upper side of the table top, the shorter angular portion of the right angularly formed arm being of a length 100 105 110

slightly greater than the thickness of the table top in order that the attaching finger of plate 6 may be swung outwardly from the same to a position at substantially right angles thereto, whereupon the table leg will be in its folded or non-supporting position.

When the table leg is swung to its "set up" position, the squared upper end of the same will abut a portion of the under side 10 of the table top in the manner shown in the Figure 3, while the right angularly formed arm 3 will afford an effectual connection and brace between the same and said table top. To prevent undue movement of the arm 3 together with the leg 2 with relation to the table top, a forked locking member indicated by the numeral 11 is provided and is adapted to have its oppositely disposed legs passed through the extended portions of the staples or eyelets 10 passing through the openings 5 in the angularly disposed portions of said arm. Thus, said arm will be prevented from having material movement with relation to 25 the table top or leg and hence, the latter will be firmly secured in its "set up" position. To prevent loss of the locking device 11, a suitable connection such as a chain 12 may be and preferably is connected to the looped handle portion of the same and to an adjacent portion of the table top.

Manifestly, the construction shown is capable of considerable modification and such modification as is within the scope of 35 our claims, we consider within the spirit of our invention.

We claim:

1. A hinge comprising a substantially right angularly formed arm having bearing sleeves on its opposite ends, attaching fingers having each a bearing sleeve on certain of their ends arranged adjacent the opposite ends of said arm, and pintles passing through the adjacent bearing sleeve on said arm and fingers.
2. A hinge comprising a substantially right angularly formed arm having spaced

bearing sleeves on its opposite ends, attaching plates having each a bearing sleeve on certain of their ends arranged adjacent the opposite ends of said arm, pintles passing through the adjacent bearing sleeve on said opposite ends of the arm and said attaching plates, laterally disposed staples carried on certain of the sides of said attaching plates adapted to be received through corresponding openings in the angular portions of said arms, at times, and locking means engageable with the extended portions of said staples upon engagement of the same in the openings in said angular portions of the arm.

3. In combination with a folding table including a top and supporting legs, hinges connecting said legs to the under side of portions of said top comprising a substantially right angularly formed arm having bearing sleeves formed on its opposite extremities, attaching plates having bearing sleeves formed on its opposite extremities, attaching plates having a bearing sleeve on certain of their ends arranged adjacent the bearing sleeve on said arm, pintles passing through said adjacent bearing sleeves for inter-connecting the same, one of said plates being connected to the upper side of the adjacent table leg and the other attaching plate being connected to an adjacent portion of the under side of the table top, outwardly extending staples on certain of the sides of said attaching plates adapted to be received through openings in the angular portion of said arms, at times, and a forked locking member adapted to have the oppositely disposed legs thereof passed through said staples upon their engagement through the openings in said right angularly formed arm connected to the under side of an adjacent portion of the table top.

In witness whereof we have hereunto set 90 our hands:

ELMER O. ROBERTS.
RAYMOND F. DOTSCH.
